(57) **CLAIM**

The ornamental design for a table/desk, as shown and described.

DESCRIPTION

FIG. 1 is a top, left side perspective view of a table/desk showing of my new design;

FIG. 2 is a front view thereof, the rear view being identical thereto;

FIG. 3 is a left side view thereof, the right side being identical thereto;

FIG. 4 is a top view thereof;

FIG. 5 is a bottom view thereof;

FIG. 6 is an exploded top, left side perspective view;

FIG. 7 is a bottom, right side perspective view;

FIG. 8 is a top, left side perspective view thereof shown in an alternative raised position of use;

FIG. 9 is a front view thereof, the rear view being identical thereto;

FIG. 10 is a left side view thereof, the right-hand side being identical thereto;

FIG. 11 is a top view thereof; and,

FIG. 12 is a bottom view thereof.

The broken lines in the drawings show portions of the table/desk that form no part of the claimed design. The table/desk is shown with a symbolic break line in its length. The appearance of any portion of the table/desk between the break lines forms no part of the claimed design.
